UNITED STATES PATENT OFFICE.

JOHN F. WALTHOUR, OF SAN FRANCISCO, CALIFORNIA, ASSIGNOR OF
ONE-HALF OF HIS RIGHT TO WALTER H. CHENERY, OF SAME PLACE.

ROWING-MACHINE.

SPECIFICATION forming part of Letters Patent No. 228,845, dated June 15, 1880.

Application filed August 16, 1879.

To all whom it may concern:

Be it known that I, JOHN FRANKLIN WALTHOUR, of San Francisco, in the county of San Francisco and State of California, have invented a certain new and useful invention or Improvement in Rowing-Machines; and I do hereby declare that the following is a full, clear, and exact description of the same, reference being had to the accompanying drawings, and the letters of reference marked thereon.

My invention has for its object to provide a rowing machine or apparatus to be used in halls, parlors, and buildings on land for exercise, or on ships and vessels for the instruction of sailors and marines afloat.

It consists of a rocking frame or a frame on rockers; across the bottom of the machine, at right angles to the frame, extended supporting-arms, upon the extremity of which the oars are pivoted. These arms are jointed and are supported by stay-rods running from them and attached to the frame.

Along the gunwale or sides of the frame are friction-guides provided with metal bearings, which, by set-screws and springs, are made to tighten upon the oars, so that they are moved with a greater or less application of power or exertion of the operator. At the same time the oars must be feathered before each stroke is made; all of which, together with other details of construction, will hereinafter be more fully set forth.

Referring to the accompanying drawings, Figure 1 is a perspective view of my improved rowing-machine. Figs. 2 and 3 are detail views of the gunwale-bars, showing the modes of constructing the upper one for strokes of different length. Fig. 4 is a transverse section amidships through the line x x , Fig. 1.

A represents the frame of my machine, mounted upon rockers a a a , as shown, so as to impart to the machine, when the stroke is made, a more near approximation to the motion or settling of a row-boat in water, as the machine or frame will settle or yield to the operator as the strokes are made.

Athwart the machine, and at right angles to the body, extend arms or bars B B, which are jointed and hinged at b b , and the same pin which holds and supports the hinges b also

supports and holds the outer ends of brace-
rods d d , which connect by bolts and nuts d' with the frame.

To the ends of the arms B B are pivoted the oars by vertical pivots or swivels e , having eyes, through which bolts attached to the ends of the oars pass, the swivels and oars both being held by set-nuts e' e'' . Thus it will be seen that the lower ends of the oars are confined to said arms by pivots which admit of their being moved in an easy manner in a horizontal or rotary position. When the machine is not in use these arms may be folded up out of the way without unshipping the oars.

The sides or gunwales of the machine are constructed of two strips or pieces of deal, D D', with longitudinal slots or openings, which are made by cutting away a portion of each deal, which form frictional surfaces, which are metal-lined, and along which the oars are plied. The lower strips are rigidly fastened to the ends and center of the frame, and the upper strips are removable and provided with vertical pins f f , which pass through the lower strip or deal a sufficient distance to receive a spring, g , and thumb-screw g' , so that a greater or less tension may be imparted to the springs, and a greater or less power exerted to raise the upper strip or deal in pulling the metal-covered oars along the metal-lined slots, as the friction will become greater or less as the thumb or set screws are tightened or loosened through the medium of the springs. These frictional bearing-surfaces are one of the most important features of my invention, as by this means the operator or oarsman can regulate the resistance of the frictional bearing-surfaces upon the metal bearing-surfaces of the oars to his capacity or increasing capacity of plying the oars.

It should here be observed that the ends h h of the slots are made wider, so as to give sufficient space in which to feather the oars, which should be done at the commencement of each stroke by turning the oars on their pivots and in the enlarged heads of the slots. Where a shorter stroke is necessary, as when ladies or children are exercising, the upper deal or gunwale, D'', having a shorter slot, is employed.

The body or shell of the machine is con-

structed, as shown, with the foot-brace board E and seat F, movable on ways *i i*, having in view a proper adjustment to the height of the operator, and all of the parts of the machine 5 are put together with bolts and screws, so that it can be taken apart and shipped, occupying but a small space.

Having thus described my invention, what I claim, and desire to secure by Letters Patent, is—

1. In a rowing-machine, the horizontally-slotted frictional oar-bearings or gunwales D D', the upper portion, D', being adjustable, by means of the springs *g g*, upon the guide-pins 15 *f f*, substantially as and for the purpose specified.

2. In combination with a rowing-machine

mounted on rockers, the oars pivoted at their lower ends and arranged to operate in frictional bearings, substantially as described. 20

3. In a rowing-machine, the combination, with the shell A, having the gunwales provided with longitudinal openings, of the oars pivoted to the folding arms or bars B B, and operating in the frictional bearing-surfaces of 25 said openings, all combined and arranged substantially as herein set forth and described.

In testimony that I claim the foregoing I have hereunto set my hand and seal this 15th day of July, 1879.

JOHN F. WALTHOUR. [L. S.]
